CLAIM

The ornamental design for a satellite dish cover, as
shown and described.

DESCRIPTION

FIG. 1 is a top perspective view of a satellite dish cover
showing my new design;

FIG. 2 is a bottom perspective view thereof;

FIG. 3 is a top perspective view of a second embodiment
of the satellite dish cover illustrated in FIG. 1; and
FIG. 4 is a bottom perspective view of the embodiment
disclosed in FIG. 3.

FIG. 1

FIG. 2

FIG. 3

FIG. 4
